(57) **CLAIM**

The ornamental design for a chain connector, as shown.

DESCRIPTION

FIG. 1 is a perspective view of a chain connector in accordance with the present invention;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a sectional view taken along line 8-8 of FIG. 2. The broken line showing of the chain connector illustrates environment and forms no part of the claimed design.
